BRIDGING PLUG AND SETTING TOOL

Luther C. Thaxton, Casper, Wyo., assignor to
 Lane-Wells Company, Los Angeles, Calif., a
 corporation of Delaware

Application May 8, 1948, Serial No. 25,925

1 Claim. (Cl. 166—13)

1

This invention relates generally to well packing devices and more particularly to bridging plugs and tools for setting bridging plugs and the like devices within well boreholes and casings.

Packer devices particularly of the bridging plug type are usually employed for the well known purpose of closing or sealing off a lower portion of the well or to separate upper and lower sections thereof for various purposes. Such bridging or plugging operations are often employed, for example, when a lower zone in an oil well has ceased to be sufficiently productive, or where the well bore has been found to extend into water-producing zones or thief sands, or for any other reason it becomes desirable to plug back or close-off a lower zone or portion of the well and produce from a higher zone in the well. In some such cases where the bottom zone into which a well has been drilled fails or ceases to be sufficiently productive, it may then be desirable to explore and test a number of higher zones for their possible productivity.

Under such conditions it is the usual practice first to position and set a bridging plug in the well at a point a short distance above the top of the lowermost zone or portion of the well bore to be sealed off and then to test another prospective zone intersecting the well above the set bridging plug. If the second zone also proves to be unproductive another bridging plug may be set in the well bore above the top of the second zone thus tested and another test made. This testing process may be repeated step by step at successively higher zones as many times as is desired.

Heretofore the process and apparatus required for lowering, positioning and setting a packer in the well and for releasing the setting tools has been more complicated, expensive and time-consuming than is desirable, particularly under such conditions as heretofore mentioned where a relatively large number of bridging plugs must be set throughout a considerable length of the well. Furthermore, the setting of bridging plugs has usually required that special servicing, hoisting and control equipment be employed other than those available as standard equipment about a drilling and producing well. This latter situation has heretofore resulted in substantial limitations and restrictions in the use of bridging plugs in wells particularly in remote parts of the world where the special service facilities and skills desirable for such operations are usually unavailable.

It is, accordingly, an object of this invention 55 to provide bridging plug and setting tool apparatus which will eliminate many of the undesirable and limiting features heretofore prevalent in bridging plug and setting tool operations and apparatus.

It is also an object to provide a bridging plug and setting tool therefor, of novel construction and which is simple, inexpensive and dependable and capable of rapid and efficient operation.

10 It is also an object of this invention to provide improved well bridging plug apparatus which may be serviced and set in a well without the use of any equipment other than that always present as standard equipment in the drilling, producing or maintenance of wells.

The objects of the invention are accomplished, in general, by a novel setting tool and combination of setting tool and packer device which may be run to the desired depth, set and released in 20 set condition in a well on and by use, preferably, of a cable such as a sand line or that used in standard cable tools, all without requiring any equipment or personnel other than those usually available for or during the drilling, production or maintenance operations of a well.

These and other objects, advantages and features of novelty will be evident hereinafter.

In the drawings which show by way of illustration, preferred embodiments of the invention, 30 and in which like reference characters designate the same or similar parts throughout the several views:

Figure 1 is a longitudinal elevational view of the general assembly of the bridging plug and setting tool as it appears when assembled ready to be lowered into a well or when suspended within a well casing just prior to setting.

Figures 2 and 2a are enlarged fragmentary longitudinal sectional views of adjoining upper 40 and lower portions respectively of the apparatus of Figure 1 showing its assembled appearance while being lowered and just prior to setting in a casing.

Figures 3 and 3a are longitudinal sectional views of adjoining upper and lower portions respectively of the apparatus showing its appearance just after completion of the setting stage.

Figure 4 is a longitudinal sectional view of a fragmentary portion of the upper end of the bridging plug mandrel and a lower end portion of the setting tool strut connections showing their appearance just after disconnection from one another following the completion of the setting stage as illustrated in Figure 4.

Figure 5 is an enlarged cross-sectional view taken on line 5-5 of Figure 2.

Figure 6 is an enlarged fragmentary longitudinal sectional view taken on line 6-6 of Figure 5.

The apparatus is as follows:

Referring now to the drawings and primarily to Figure 2a, the packer portion or body of the apparatus comprises a centrally located, elongated tubular body or mandrel 10 of substantially uniform external diameter throughout its length and closed and terminating at its lower end by a nose piece or shoe portion 11 of slightly increased diameter, an upwardly facing annular shoulder 12 being thus formed at the junction of said mandrel body and said shoe portion. A plug 22 threaded into the bottom of the shoe 11 closes a threaded connection which may be employed for attachment of other apparatus such as, for example, a lower string of tubing or a circulating valve not shown. At the lower intermediate portion, the mandrel is formed with a short section 13 of slightly reduced diameter about which a split ring 14 is placed and is therein longitudinally slidably retained to act as a means for retaining an annular packing body 37 in place upon the mandrel as more fully described hereinafter. At an upper intermediate portion, the mandrel is formed with a length of downwardly facing ratchet grooves or buttress threads 16 adapted to ratchet through and make one-way locking engagement with a correspondingly toothed split, lock ring 17. The lock ring 17 is retained in an inwardly facing, annular groove formed between upper and lower, threadedly interconnected halves 18 and 19 respectively of a lock ring adapter fitting 20 hereinafter also more fully described. A shallow annular groove 21 is formed in the upper portion of the mandrel 10 adjacent the upper end thereof which serves as a detent to receive the inner toothed portion of the lock ring 17 when the packer is in the unset condition as illustrated in Figures 2 and 2a.

The upper end of the mandrel 10 is provided with internal threads 23 into which a relatively short, externally threaded connector sleeve 24 is screwed.

A plurality of lower, wedge shaped slips 25 having downwardly facing serrations or wickers are normally positioned about the lower end of the mandrel 10 as shown in Figure 2a and retained there by a slip retainer ring 26, attachment between each of said slips and said retainer ring being effected by a dove-tail interconnection comprising a radially directed dove-tail slot 27 formed in the upper face of the retainer ring 25 into which a dove-tail 28 formed on the lower base end of the slip, fits and has limited freedom for radial sliding motion therein to permit radial expansion of the slip.

A like set of upper slips 32 having upwardly facing serrations is provided about the upper portion of the mandrel 10 adjacent the lower end of the beforementioned lock ring adapter fitting 20 and these slips are similarly provided with dove-tail connections as shown at 33 to the lower half 19 of the lock ring adapter fitting 20 permitting radial expansive movement of said slips.

Intermediate the beforementioned sets of upper and lower slips are a lower, upwardly diverging slip cone 35, an upper, downwardly diverging slip cone 36 and a resilient, sleeve shaped packing element 37 intermediate the said slip cones, all longitudinally slidably retained upon 70

the mandrel 10 except as initially restricted by various releasable interconnecting means hereafter described. The upwardly facing base end 38 of the lower slip cone 35 and the downwardly facing base end 39 of the upper slip cone 36 serve as lower and upper abutments respectively between which the resilient packing element 37 is retained and in operation is adapted to be compressed longitudinally for deformation or expansion radially into sealing engagement with a surrounding borehole wall or casing.

The bore of the packing sleeve 37 is formed with an inner annular groove 40 adjacent its lower end to receive the outer portion of the hereinbefore mentioned retaining ring 14. The ring 14 is usually, although not necessarily, placed in the packer body at the time of its manufacture and thus may be firmly bonded thereto to form a unitary part thereof.

Each of the lower slips 25 is provided with a positioning pin fixed therein as shown at 41, having its inner end extending with a relatively loose fit into a shallow socket formed in the mandrel as shown at 42. Each of the slips of both the upper and lower set of slips is initially anchored to the slip cone face upon which it bears, by means of a shear pin or screw as shown respectively at 43 and 44.

The lower set of slips 25 is urged upwardly by means of a plurality of coil springs 45 retained in circumferentially spaced holes extending axially through the flanged or shouldered portion 12 of the nose piece 11 and acting under compression between the lower face of the slip-retainer ring 26 and threaded, spring-retainer plugs 46.

The lower packer-abutting end 39 of the upper slip cone 36 is formed with a short counterbore 48 terminating at its inner upper end in a chamber or upwardly converging conical shoulder 49. The lower end portion of the slip cone outside of the beforementioned counterbore, is formed with a downwardly converging conical surface as shown at 50, terminating at the intersection of its conical surface with the inside cylindrical surface of the counterbore 48, in a downwardly directed, relatively sharp beveled edge 52. The upper adjacent end of the resilient packing sleeve 37 is formed with an outer conical end portion adapted to fit and normally abut the before-described conical surface 50 of the slip cone 36. The packing sleeve is also provided with a longitudinally directed cylindrical slit 55, commencing at the inner terminus of the conical surface 50 of the packer and extending longitudinally inward or downward for a short distance along a cylindrical surface formed by the downward projection of the inside cylindrical surface of the slip cone counterbore 48. A pair of separate, concentric, annular portions of the upper end of the packing 37 are thus formed, separated by the slit 55, the inner annular portion 56 being adapted to be thrust into the inner annular space within the counterbore 48 around the packer mandrel and the outer annular portion 57 being adapted to be thrust into the outer annular space formed between the outside surface of the lower end portion of the slip cone 36 and the inside surface of a surrounding casing as shown in Figure 3a upon application of longitudinal compressive force to the packing sleeve 37. The lower overlapping ends of the slips 32 serve to seal off the upper end of this annular space into which the packer is thrust as shown in Figure 3a.

Referring now primarily to Figure 2, in which

the upper, setting tool portion of the packer apparatus is illustrated, a tubular adapter sleeve 60 is shown extending upwardly from a threaded connection 61 located at the top of the locking ring adapter fitting 20. Upon the top end of the adapter sleeve 60 is an auxiliary, well bore wall or casing gripping means comprising a dog retainer head 62 formed with an axial bore 63. The dog retainer head 62 is formed with two pairs of diametrically opposite, radial slots 64, 64a and 65 and 65a extending downward through the annular top portion of the head as best shown in Figures 2 and 5. Each slot contains a cam-shaped gripping member or dog 66 pivotally supported therein adjacent its lower end upon a pin connection 67 which extends cross-wise through the lower part of the slot. The upper, cam-shaped, free end of each dog 66 is provided with serrations as shown at 68 and the outer side thereof is provided with a longitudinal groove or recess 69 into which the top portion of a helical spring 70 normally extends to a pin connection 71 therein as shown in Figures 2, 3 and 6. The opposite or lower end of each of the springs 70 extends downwardly through a longitudinal slot 72 formed in the exterior surface of the head 62 to a suitable fastening to the head in the lower portion of the slot as shown at 73. The springs 70 acting in tension urge the dogs 66 to pivot outwardly about their pivot pins 67 to extended positions as shown in Figures 2, 3, 5 and 6.

It is to be noted that the general curvature of the upper or outer serrated ends of the dogs 66 opposite their pivots 67 are eccentric to the pivots, or cam-shaped, to adapt them to rock into firm gripping engagement with the inside surface of a casing or borehole wall upon imparting upward movement to the apparatus relative to such casing or borehole.

A setting sleeve 77 having an upper tubular shank portion 78 of larger diameter than the lower tubular strut portion 79 is normally positioned, as initially assembled, with the shoulder 80, formed at the juncture of said shank and said strut, resting upon the slotted, annular, top end surface of the dog retainer head 62 as shown in Figures 1, 2 and 6. The upper end of the setting sleeve shank 78 is provided with suitable external threads 81 adapted to make screwed connection with a cable or so-called rope socket 82 suspended from a cable 83 as illustrated in Figures 1 and 2 when the apparatus is run into the well and set on a cable. Adjustably threaded into internal threads formed in the lower end of the strut portion 79 of the setting sleeve 77 is a short, externally threaded connector member 84 the lowermost unthreaded end portion of which extends into the top opening of the beforementioned connector sleeve 24 and is secured there by means of a shear pin 84a which extends cross-wise through holes drilled through both the connector sleeve 24 and the connector member 84. An adjusting nut 85 and lock nut 86 carried on the lower threaded portion of the connector member 84 serve by proper adjustment against the top of the connector sleeve 24 to relieve or protect the shear pin 84a from any downward thrust or compression forces which may be applied through the setting sleeve. A lock nut 87 carried on the intermediate, threaded portion of the connector member 84 serves to secure the adjusted position of the connector member within the lower end of the setting sleeve strut 79.

A shear pin 96 making a driving fit through a drilled hole in the lower end portion of the adapt-

er sleeve 60 extends into an aligned, drilled hole or socket formed in the upper end of the mandrel 10. The shear pin 96 serves as a means for initially positioning and locking the packer mandrel 10 relative to the setting mechanism and to support the weight of the sleeve 60 and head 62 which might otherwise tend to force the upper slips 32 and slip cone 36 downward against the packer sleeve 37 and thus tend to cause premature setting of the packer.

Upper and lower, lateral fluid pressure equalization and circulation openings 100 and 101 are provided through the walls of the shank and strut portions respectively of the setting sleeve 77.

The operation is as follows:

In running in and setting the bridging plug apparatus of this invention the combined bridging plug and setting tool are assembled as shown in Figure 1 and lowered into the borehole or casing upon a cable 83 to the point at which it is desired to bridge the well.

As the apparatus is lowered into the casing on the cable, the dogs 66 will merely drag in trailing attitude along the inside surface of the casing without affording any substantial resistance to the downward motion. However, upon arriving at the position at which it is desired to set the bridging plug and upon stopping the downward motion and applying upward tension through the cable tending to elevate the apparatus, the dogs being already positioned in the beforementioned extended and trailing attitude will immediately cramp or rock outward into locking engagement with the inside surface of the casing and resist upward motion of the dog retainer head 64.

The upward tension thus applied to the cable is transmitted through the setting sleeve 77, the connector member 84 and thence through the shear pin 84a and the connector sleeve 24 to the top of the bridging plug mandrel 10. The upward force thus applied to the bridging plug mandrel 10 tends to move the said mandrel 10 upward with respect to the dog retainer head 62 and adapter sleeve 60 to a position such as that illustrated in Figure 3. However, shear pin 96 initially resists such relative motion until the upward force applied to the mandrel 10 reaches the shearing strength of the pin 96. Upon shearing of the pin 96 the upward force thus applied to the bridging plug mandrel 10 is rather suddenly transferred downward through the lower portion of the mandrel to the nose or shoe 11 and from there is transmitted upward from the shoulder 12 of the nose or shoe 11 through the bottom slip retainer ring 26, lower slips 25, shear pin or screw 43, lower slip cone 35, packing element 37, upper slip cone 36, shear pin or screw 44, upper slips 32, and thence through the lock ring adapter fitting 20 and the adapter sleeve 60 to the dog retainer head 62 and thence finally through the dogs 66 to the casing. The force thus applied after first shearing of the slip shear pins or shear screws 43 and 44 thereby permitting the upper and lower slips 32 and 25 to move outward upon the surface of their respective slip cones 36 and 35 into gripping engagement with the inside surface of the well casing. Following this and upon further application of upward force through the mandrel 10 the slip cone 35 is caused to move upward relative to the slip cone 36 a distance sufficient to laterally compress and radially expand the resilient or deformable packing sleeve 37 into sealing engagement with the inside sur-

face of the surrounding casing, all as illustrated in Figures 3 and 3a.

At this stage in the setting process the bridging plug mandrel 10 will have been moved upward relative to the lock ring adapter fitting 20 a distance sufficient to carry the ratchet grooves or buttress threads 16 of the mandrel upward through and into locking engagement with the lock ring 17. The bridging plug is thereby locked in the set condition within the casing with both the upper and the lower sets of slips in holding engagement with the inside surface of the casing as shown in Figures 3 and 3a.

After setting the apparatus in the casing as hereinbefore described continued and increased upward force is applied through the cable 83 and the setting sleeve 77 finally resulting in the shearing of the shear pin 84a thereby resulting in the disconnection and separation of the setting sleeve 77 and the connector member 84 from the connector sleeve 24 in the manner illustrated in Figure 4. If desired a set of jars may be placed immediately above the setting tool to facilitate this latter disconnecting operation. The portion of the setting tool remaining connected to the cable 83 including the socket 82, the setting sleeve 77 and with the connector member 84 attached, may then be withdrawn from the well casing. The several retainer members, shear pins and screws hereinbefore mentioned are designed to shear in the order named, namely, first pin 96, followed by screws 43 and 44 and finally pins 84a. Normally pins 41 are not sheared but merely move outward laterally with the lateral motion of the slips 25, thereby simply withdrawing the inner ends of the pins from the sockets 42 in the mandrel. The pins 41 serve, prior to setting of the packer to hold the slips 25 retracted and bottom against the shoe shoulder 12 against the upward force of coil springs 45. The force of the coil springs 45 is thus prevented from being applied against the bottom of the packing sleeve 37 which might otherwise result in premature setting of the packing during lowering of the device into the well.

Ordinarily the lower slips 25 and their retaining ring 26 remain, before and after setting, bottomed upon the upper surface of the shoulder 12 of the shoe 11. However, in event movement of the plug should occur after setting such that the resultant relative motion between the lower slip cone 35 and the shoulder 12 tended to release the lower slips 25, then the coil springs 45 would force the said slips to follow any such motion of the slip cone in wedging position between the slope of the cone and the inside surface of the surrounding casing.

While the apparatus and operation of this invention has been described as advantageously be employed in some cases in connection with a

10

cable supporting and lowering means, it may also be employed in some cases in connection with a suitable tubing string or pipe.

It is to be understood that the foregoing is illustrative only and that the invention is not limited thereby but may include various modifications and changes made by those skilled in the art without distinguishing from the spirit and scope of the invention as defined in the appended claim.

I claim:

A bridging plug setting tool for setting a bridging plug, which bridging plug includes a mandrel, an annular packing body surrounding the mandrel, upper and lower slips above and below the packing body respectively, an upwardly facing shoulder on said mandrel below said lower slips, and an adapter fitting surrounding said mandrel above said upper slips and having a downwardly facing shoulder, such bridging plug being adapted to be set by upward movement of the mandrel relative to the adapter fitting, said setting tool comprising a tubular adapter sleeve secured to and extending upwardly from said adapter fitting, upwardly and outwardly extending gripping dogs pivotally mounted in said tubular adapter sleeve for pivotal movement in vertical planes, said gripping dogs being biased toward outwardly extended positions whereby said gripping dogs permit free downward movement of said tubular adapter sleeve through a surrounding well casing but engage and grip such casing to prevent upward movement of said tubular adapter sleeve therein, a setting sleeve removably extending in telescoping relation into the upper end of said tubular adapter sleeve, a frangible connection between the lower end of said setting sleeve and the upper end of said mandrel, and means for attaching a cable to the upper end of said setting sleeve for applying an upward force to said setting sleeve while said gripping dogs prevent upward movement of said tubular adapter sleeve to move the upwardly facing shoulder on said mandrel upwardly toward said downwardly facing shoulder on said adapter fitting to thereby set the bridging plug and to subsequently break with said frangible connection to permit removal of said setting sleeve from the well.
